UNITED STATES PATENT OFFICE.

WILLIAM OREM, OF BALTIMORE, MARYLAND.

DESIGN FOR A BOTTLE.

48,734.

Specification for Design.

Patented Mar. 14, 1916.

Application filed January 3, 1916. Serial No. 70,038. Term of patent 7 years.

To all whom it may concern:

Be it known that I, WILLIAM OREM, a citizen of the United States, residing in the city of Baltimore, State of Maryland, have invented a new, original, and ornamental Design for Bottles, of which the following is a specification, reference being had to the accompanying drawing, forming part thereof.

The figure is a perspective view of a bottle showing my new design.

I claim:—

The ornamental design for a bottle, as shown.

WM. OREM.

Witnesses:

EDW. L. RUSSELL,
W. A. MORRISON.
